UNITED STATES PATENT OFFICE

JACOB TELLER AND ARTHUR P. SCHULZ, OF NEW YORK, N. Y., ASSIGNEES, BY MESNE ASSIGNMENTS, TO TELLER STOVE DESIGNING CORPORATION, A CORPORATION OF NEW YORK

DESIGN FOR A GAS OR ELECTRIC WATER HEATER

Application filed September 4, 1931. Serial No. 41,024. Term of patent 7 years.

To all whom it may concern:

Be it known that we, JACOB TELLER and ARTHUR P. SCHULZ, citizens of the United States, and residents of New York city, in the county of New York and State of New York, have invented a new, original, and ornamental Design for Gas or Electric Water Heaters, of which the following is a specification, reference being had to the accompanying drawings, forming a part thereof.

Figure 1 is a perspective view of the water heater.

Figure 2 is a top plan view of the water heater.

The design of the water heater is symmetrical on all sides.

We claim:

The ornamental design for a gas or electric water heater, as shown and described.

JACOB TELLER.
ARTHUR P. SCHULZ.
